ELECTRIC SCISSORS

John M. Zuro, Park Ridge, Ill. (% The Grant Company,
4149 Milwaukee Ave., Chicago, Ill. 60641)

Filed Feb. 20, 1969, Ser. No. 15,856

Term of patent 14 years

Int. Cl. D8—02

U.S. Cl. D8—61

FIG. 1 is a perspective view of an electric scissors, showing my new design;

FIG. 2 is a left side elevation view;

FIG. 3 is a front elevation view;

FIG. 4 is a right side elevation view of an electric scissors showing another form of my new design wherein a foot member is attached to the lower blade member;

FIG. 5 is a rear elevation view thereof; and

FIG. 6 is a bottom plan view thereof.

I claim:

The ornamental design for an electric scissors, substantially as shown and described.
